UNITED STATES PATENT OFFICE.

ALBERT EDMUND HUDSON, OF CALGARY, ALBERTA, CANADA.

SPARK-ARRESTER.

1,268,011.

Specification of Letters Patent. Patented May 28, 1918.

Application filed October 4, 1917. Serial No. 194,740.

To all whom it may concern:

Be it known that I, ALBERT EDMUND HUDSON, a subject of the King of Great Britain, and a resident of the city of Calgary, in the 5 Province of Alberta and Dominion of Canada, have invented certain new and useful Improvements in Spark-Arresters, of which the following is the specification.

This invention relates to improvements in 10 spark arresters, particularly adapted for use on locomotive boilers and is of that type in which baffles or deflectors are located in the smoke box of a locomotive boiler, and in the path of the products of combustion from the 15 furnace, so as to intercept and deflect the cinders from their course while passing through the smoke box to the atmosphere. As the cinders or sparks travel at great velocity, their coming in contact with the baffles or deflectors changes their course, and by repeated deflections the sparks are crumpled or extinguished and retarded sufficiently to permit the cinders to burn themselves out before reaching the atmosphere, thus effectively 20 destroying the sparks and eliminating all fire hazard.

Further objects of the invention are to effectively destroy the spark without impairing the draft and efficiency of the boiler, to 25 so construct the arrester, that it may be readily installed, and removed from the smoke box of the boiler, to permit of each baffle plate of the arrester being individually removable, so that it may be easily replaced by a new one when found necessary, and further, to permit of the several parts being capable of ready inspection and adapted to better perform the functions required 35 of them.

With the above and other objects in view 40 the invention consists essentially of the improved construction particularly described and set forth in the following specification and accompanying drawings forming part 45 of the same.

In the drawings:

Figure 1 is a fragmentary longitudinal section of a locomotive boiler showing the improved spark arrester installed therein.

Fig. 2 is a sectional end elevation of the boiler showing the location of the baffle plates of the spark arrester.

Fig. 3 is a fragmentary perspective view 55 of one of the baffle plate supporting members.

Like characters of reference refer to like parts in the several figures.

In the drawings: A represents a locomotive boiler of any usual construction provided with a transversely extending wall 10, 60 which is located in the smoke box B in front of the tube plate C, the said wall extending downwardly and partially across the smoke box, being provided with an offset portion 11, which is designed to lie in a substantially horizontal plane, the said offset portion terminating in a vertically disposed flange 12, which forms with the inner wall of the lower portion of the smoke box a passage way 13 through which the products 70 of combustion from the furnace pass.

A tapered conduit 14 is located between the bottom of the smoke box B and the offset plate 11 and the exhaust steam is designed to pass through this conduit and 75 thence through the conduits 15 and 16 located immediately below the smoke stack 17.

A screen 18 extends around the edge of the offset plate 11 and terminates at the inner wall of the smoke box B, the several 80 parts so far enumerated being the facsimile of those described in my United States application No. 109,917, filed July 18th, 1916; these parts are not deemed to form a part of the present invention and are only described 85 for the purpose of thoroughly explaining the location of the baffles and the manner in which the same will arrest the sparks passing through the smoke box to the atmosphere.

In front of the flange 12 and screen 18 a plurality of angularly disposed deflectors or baffle plates 19 are located, each of the deflectors or baffle plates being carried by a rod or bar 20 which is adapted to engage 95 with the notches 21 in the longitudinally extending carrier bars 22.

It will be seen by reference to Fig. 2 that some of the longitudinal carrier bars 100 are rigidly attached to the inner wall of the smoke box, while others are arranged in pairs on opposite sides of the vertical supports 23. The baffle plates 19 are arranged in a series of superimposed rows each staggered relatively to the others and the baffle 105 plates are made in three sections so that they can be readily positioned in the smoke box B.

The bars 20 are thus supported at the ends in the notches 21 of the longitudinally ex- 110

tending carrier bars 22 and these notches are angularly disposed so that tortuous passage ways extend upwardly between the baffle plates.

5 In assembling the arrester the side longitudinally extending carrier bars 22 are secured to the inner wall of the smoke box B and the intermediate carrier bars 22 are arranged in pairs on each side of the supports 10 23. The bars 20 carrying the baffle plates 19 are now engaged at the ends with the notches 21 in the bars 22 and each section of the baffle plates thus built up in the manner above described.

15 When a locomotive fitted with this type of arrester is working, the products of combustion after passing through the tubes pass under the offset portion of the plate 10 and through the opening 13 where they come 20 into contact with the baffle plates 19, the opposite rows of which are angularly disposed relatively to each other.

On the products of combustion passing upwardly through the tortuous passage ways 25 between the baffle plates the sparks impinge on the angularly disposed plates and so become extinguished. The baffle plates 19 are preferably made of screening, the mesh of which will depend to a large extent on the 30 fuel being used.

From this description it will be seen that

I have invented a spark arrester, the baffle plates of which are readily removable and can be removed with a minimum of time and labor, the cost of installation being extremely low and the several parts being arranged for ready inspection. 35

As many changes could be made in the above construction and many apparently widely different embodiments of my invention within the scope of the claim constructed without departing from the spirit or scope thereof, it is intended that all matter contained in the accompanying specification and drawings shall be interpreted as 40 45 illustrative and not in a limiting sense.

What I claim as my invention is:

In a spark arrester, a plurality of pairs of uprights, a plurality of spaced cross pieces connecting the pairs of uprights, the upper 50 edges of the cross pieces being notched, the notches of adjacent pieces being oppositely inclined, and baffle plates having bars, the bars adapted to fit into and be carried by the notches. 55

In witness whereof I have hereunto set my hand in the presence of two witnesses.

ALBERT EDMUND HUDSON.
